UNITED STATES PATENT OFFICE

104,097

DESIGN FOR A MAT LINK

Arthur S. Galkin, Providence, R. I.

Application September 30, 1936, Serial No. 65,081

Term of patent 7 years

To all whom it may concern:

Be it known that I, Arthur S. Galkin, a citizen of the United States, residing at Providence, in the county of Providence and State of Rhode Island, have invented a new, original, and ornamental Design for Mat Links, of which the following is a specification, reference being had to the accompanying drawing, forming part thereof.

In the accompanying drawing:—

Fig. 1 is a perspective view of the mat link showing my new design, and,

Fig. 2 is a side elevational view of the same.

The characteristic feature of my design resides in an arrangement of a series of tubular shaped portions, the outer surfaces of which are corrugated, and which are joined together at their adjacent edges to form a continuous mat link.

I claim:—

The ornamental design for a mat link, substantially as shown and described.

ARTHUR S. GALKIN.
